UNITED STATES PATENT OFFICE.

LOUIS PARET, OF UNION HILL, NEW JERSEY, ASSIGNOR TO THE BIGELOW CARPET COMPANY, OF MASSACHUSETTS.

DESIGN FOR CARPET.

SPECIFICATION forming part of Design No. 27,412, dated July 20, 1897.

Application filed June 7, 1897. Serial No. 639,765. Term of patent 3½ years.

To all whom it may concern:

Be it known that I, LOUIS PARET, a citizen of the United States, and a resident of Union Hill, in the county of Hudson and State of New Jersey, have invented a new and original Design for Carpet and Border, of which the following is a specification.

This invention comprises two parts—namely, the design A for a carpet and the design B for a border; and I do hereby declare that the drawing accompanying this specification conveys to any one a clear understanding of the same and is sufficient to enable such person to use my invention.

The design A is characterized by large clusters of flower forms and festoons of flower forms.

The design B is characterized by an inner panel of large clusters of flower forms and connecting festoons of flower forms. 20

What I claim, and desire to secure by Letters Patent, is—

1. In a design for a carpet, the body A, substantially as shown.
2. In a design for a carpet, the border B, 25 substantially as shown.
3. The design for a carpet comprising the body A and the border B, substantially as shown.

In testimony whereof I have signed my name to this specification in the presence of two subscribing witnesses.

LOUIS PARET.
